Primary Examiner — Marcus Jackson(74) Attorney, Agent, or Firm — Barnes & Thornburg
LLP; Mark J. Nahnsen(57) **CLAIM**

We claim the ornamental design for a headlight, as shown and described.

DESCRIPTION

FIG. 1 is a perspective view, taken from the front, right side, of a headlight in accordance with an embodiment of my new design;

FIG. 2 is a front elevational view of the headlight shown in FIG. 1;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof; and,

FIG. 8 is a perspective view, taken from the rear, left side, of the headlight shown in FIG. 1.

The broken lines depict environmental structure for illustrative purposes only and form no part of the claimed design.

1 Claim, 8 Drawing Sheets(56)
